VIBRATORY CIRCUIT CONVERTER

Herman J. Wise, Indianapolis, Ind., assignor to
 Electronic Laboratories, Incorporated, Indianapolis, Ind., a corporation of Indiana

Application December 1, 1944, Serial No. 566,128

3 Claims. (Cl. 171—97)

1

My present invention relates to improvements in vibrator interrupting systems designed primarily for changing the current of one type to that of another, as for instance the changing of direct current from a suitable direct current source into alternating current for operating a load, or for changing the voltage of a current source to a different voltage for operating a suitable load requiring a modified voltage from that originally delivered by the source.

One of the objects of my invention is to provide a system of the above identified character, whereby a relatively high input voltage may be handled in a vibrating interrupter system without damage to the vibrating interrupter apparatus or to the contacts of the vibrating interrupter.

Another object of the invention is to provide a system of the above identified character, whereby relatively high voltages may be handled by the vibrating interrupter or vibrating interrupters of the system without disruptive arcing at the contact point of the vibrating interrupter.

A still further object of my invention is the provision of a vibrating interrupter system, whereby the vibrating interrupter may handle wide fluctuations in the input circuit without danger to the vibrating interrupter and without disruptive effects on the vibrating interrupter.

Other objects and advantages of my invention will appear more fully hereinafter in the accompanying specification and appended claims.

For the purpose of disclosing my invention, I have illustrated certain embodiments shown in the accompanying drawings, in which:

Fig. 1 is a diagrammatic view of a vibrating interrupter system, embodying my invention;

Fig. 2 is a diagrammatic view of a modified form of my vibrating interrupter system, wherein the peak inverse voltage is half that of the peak inverse of the system illustrated in Fig. 1;

Fig. 3 is a diagrammatic view of a vibrating interrupter circuit, wherein the advantages of my invention may be obtained in a rectifying circuit; and

Fig. 4 is a diagrammatic view of a further modified system, such as is disclosed in Fig. 3.

Referring to the drawings and the various modifications as illustrated, in Fig. 1, I provide a transformer 1 having a secondary coil or winding 2 and a pair of primary coils or windings 3 and 4, each having a center tap, providing in the winding 3, two winding sections 5 and 6 and in the winding 4 two similar sections 7 and 8. The center tap 9 of the winding 3 is connected to one side

2

10 of the input circuit side of the circuit, which input side may be connected to any suitable source of direct current supply. The center tap 11 of the winding 4 is connected to the other side 12 of the input circuit.

Cooperating with the transformer 1 is a vibrating interrupter 13 having a vibrating reed 14. This reed is adapted to vibrate between pairs of relatively stationary contacts, so that contacts 15 and 16 of the reed are adapted to engage alternately contacts 17 and 18 on one side of the reed and contacts 19 and 20 on the opposite side of the reed.

The outer terminal 21 of the winding 3 is suitably connected to the contact 17, while the outer terminal 22 of this winding is connected with contact 19. The outer terminal 23 of the winding 4 is connected to the contact 20, while the outer terminal 24 thereof is connected to contact 18. Therefore, during the vibration of the reed 14, when contacts 15 and 16 are in engagement with contact 17 and 18 current will flow through the sections 5 and 6 of windings 3 and 4 in one direction, indicated by the arrows. When the reed 14 moves in the opposite direction causing contacts 15 and 16 to engage contacts 19 and 20 current will be caused to flow through the winding sections 6 and 7 in the opposite direction. In each instance, the winding sections of the two windings 3 and 4 will be in series and therefore the number of turns in each winding section may be half the number of turns of that required in a conventional system, and as a result the peak inverse voltage across the oppositely disposed relatively stationary contacts will be cut in half.

In the system, for driving the vibrating reed 14, I provide a driving magnet having a driving coil 25, one terminal of which is connected to a relatively stationary contact 26 adapted normally to engage a contact 27 of the reed 14. This contact 27, through the reed 14, is connected through a resistance 28 with one side 12 of the input circuit. The opposite terminal of the winding 25 is connected through resistance 29 with the other side 10 of the input circuit. The resistances are used as a voltage divider to supply the driving magnet with a voltage lower than the input voltage to permit the use of a relatively low voltage coil. These resistances also isolate the center reed from the transformer windings. Therefore, when the circuit is initially closed, the reed 14 will be moved in a direction to open its own circuit and at the same time engage contacts 15 and 16 with contacts 17 and 18. On its rebound, the

reed 14 will engage contacts 15 and 16 with contacts 18 and 20 and again close its circuit.

In the system illustrated in Fig. 2, I have shown a system whereby the voltage across each winding section is still further reduced. In the system illustrated in Fig. 2, the transformer 4 with its secondary 2 is provided with four primary windings 30, 31, 32, and 33, each winding having a center tap so that the winding 30 will be provided with two sections 34 and 35; the winding 31 will be provided with two sections 36 and 37; the winding 32 will be provided with sections 38 and 39 and the winding 33 will be provided with sections 40 and 41.

The vibrating interrupter 13 is provided with two vibrating reeds 42 and 43. The vibrating reed 42 being provided with contacts 44 and 45 and the reed 43 being provided with contacts 46 and 47. The contacts 44 and 45 make contact, when moved in one direction, with the relatively stationary contacts 48 and 49, disposed on one side of the reed, and when moved in the opposite direction make contact with the relatively stationary contacts 50 and 51 disposed on the opposite side of the reed. The reed 43 vibrates in unison with the reed 42 and when the reed 42 is moved into engagement with contacts 48 and 49, the reed 43 will be moved to cause contacts 46 and 47 to engage contacts 52 and 53 disposed on one side of the reed and when moved in the opposite direction will engage contacts 54 and 55 disposed on the opposite side of the reed.

The center tap 56 of the winding 30 is connected to one side 10 of the input circuit. The outer terminal of the winding section 34 is connected to the relatively stationary contact 48. The outer terminal of the section 35 of the winding 30 is connected to the relatively stationary contact 50. The center tap 58 of the winding 31 is connected to the center tap 57 of the winding 32. The outer terminal of the winding section 36 is connected to the relatively stationary contact 51, while the outer terminal of the winding section 37 is connected to the relatively stationary contact 49.

The outer terminal of the winding section 38 of winding 32 is connected to the relatively stationary contact 52, while the outer terminal of the winding section 39 is connected to the relatively stationary contact 54. The center tap 59 of the winding 33 is connected to the other side 12 of the input circuit while the outer terminal of the winding section 40 is connected to the relatively stationary contact 55 and the outer terminal of the section 41 is connected to the relatively stationary contact 53.

Therefore, when the contacts 44 and 45 are in engagement with contacts 48 and 49 and simultaneously contacts 46 and 47 are in engagement with the contacts 52 and 53, current will flow from the input side of the circuit through the winding sections 34, 37, 38, and 41 in series in the direction indicated by the arrows. Likewise, when the contacts 44 and 45 of the reed 42 and 46 and 47 of the reed 43 are simultaneously engaged with contacts 50 and 51 and 54 and 55, current will flow from the input side of the circuit through winding sections 35, 36, 39, and 40 in the direction of the arrows, which is the opposite direction to that of the current flow first indicated, thereby inducing an alternating current in the secondary winding 2. Since the four windings are connected in series, the voltage across each winding is one-fourth, thus dividing the peak inverse voltage across the contacts by four.

For driving the two reeds 42 and 43, which are mechanically connected, I provide a driving magnet having a coil 60. One terminal of this coil is connected with one side 12 of the input circuit, a resistance winding 63 being included in the circuit. The opposite terminal of the winding 60 is connected to the opposite side 10 of the input circuit, a resistance 64 being included in this circuit.

10 In the system illustrated in Fig. 3, I have shown a system wherein I provide for a change of voltage without changing the character of the current, while maintaining all of the advantages of my invention. In this system, I provide a transformer 65 having a split primary winding or coil 66. The center tap of this coil 66 is connected to one terminal 10 of the input circuit. One outer terminal of the coil or winding is connected to a pair of relatively stationary contacts 67 and 68, disposed on one side of a vibrating center reed 69 and the opposite terminal of the winding 66 is connected to a pair of contacts 70 and 71 disposed on the opposite side of the reed 69. These sets of contacts are adapted to be engaged by contacts 72 and 73 on the reed 69 which are in turn connected through the reed with the opposite terminal 12 of the input circuit. This reed 69 is driven by driving contact having a coil 74, one terminal of which is connected to a contact 75 normally in engagement with the contact 76 on the reed 69, the opposite terminal of the coil being connected to the input terminal 10 of the input side of the circuit. Therefore, as the reed is vibrated between the relatively stationary contacts, current will flow alternately and in opposite directions through the winding sections of the primary winding 66, inducing an alternating current in the secondary windings of the transformer.

40 The secondary, which is adapted to be connected to the load, is provided with a pair of coils or windings 77 and 78 each having a center tap adapted to be connected to one terminal of the load and dividing the windings into sections. 45 The outer terminal of the section 79 of the winding 77 is connected to a relatively stationary contact 80 while the opposite terminal of the other section 81 of the winding 77 is connected to a relatively stationary contact 82, disposed in opposite relation with respect to the contact 80 and these two contacts are adapted to be alternately engaged by contact 83 on the reed 69.

The outer terminal of the section 84 of the winding 78 is connected to a relatively stationary contact 85 of the vibrating interrupter and the outer terminal of the section 86 of the winding 78 is connected to an oppositely disposed contact 87, these contacts adapted to be alternately engaged by the contact 88 on the reed 69. Therefore, during the vibration of the reed 69, while an alternating current is induced in the windings 77 and 78 of the secondary, this current being induced in the sections 86 and 79 in one direction and then the opposite direction in sections 78 and 81, as indicated by the arrows, is rectified to deliver the same type of current to the load as that supplied from the direct current source of supply at the desired voltage.

70 In the system illustrated in Fig. 4, substantially the same arrangement as that shown in Fig. 3 is illustrated, except that in the system illustrated in Fig. 4 the primary and secondaries are isolated from one another due to the fact that the reed structure comprises a pair of vibrating reeds 69 and 69', which are electrically separated from one

another, but mechanically connected so that they will vibrate with unison.

Suitable buffer condensers 89 are connected across the terminals of the primary windings to sustain the voltage during the off interval of the vibrating contacts. Likewise, suitable condensers 90 are connected across the vibrating and stationary contacts to prevent arcing upon the separation of the contacts. Likewise, suitable condensers 91 and resistors 92 are connected across the driver contact points to prevent arcing upon the separation of the contacts.

I claim:

1. In a transformer system, in combination, a transformer having primary and secondary windings, one of said windings including a first and a second coil, each coil having a center tap dividing each coil into first and second sections, the center tap of one coil being adapted to be connected to one side of a line and the center tap of the other coil being adapted to be connected to the other side of a line, a vibrating interrupter including a pair of contacts, one of said contacts being connected to the outer terminal of the first coil and the other contact being connected to the opposite outer terminal of the second coil and a second pair of contacts, one of said second pair of contacts being connected to the other outer terminal of the first coil and the other of said second pair of contacts being connected to the other outer terminal of said second coil and a vibrating reed operating between said pairs of contacts and alternately connecting the contacts of each pair.

2. In a transformer system, in combination, a transformer having primary and secondary windings, one of said windings including two coils, each coil having a center tap adapted for connection with a line terminal, a pair of contacts connected to the opposite outer terminals of each of said coils, a second pair of contacts, each connected to the other outer terminals of said coils and a vibrating reed operating between the pairs of contacts and alternately connecting the contacts of each pair.

3. In a transformer system in combination, a transformer having a primary and a secondary winding, said primary winding having a center tap connected to one side of a source of direct current supply and its outer terminals respectively connected to oppositely disposed contacts, said secondary winding including a first and second coil, each coil having a center tap dividing each coil into first and second section, the center tap of one coil being adapted to be connected to one side of the load circuit and a center tap of the other coil being adapted to be connected to the other side of a load circuit, a pair of contacts, one of said contacts being connected to the outer terminal of the first secondary coil and the other contact being connected to the opposite outer terminal of the second secondary coil, a second pair of contacts, one of said second pair of contacts being connected to the other outer terminal of the first secondary coil and the other of said second pair of contacts being connected to the other outer terminal of the second secondary coil and a vibrating reed operating between the contacts connected to the outer terminal of the primary winding and alternately connecting the outer terminals of the primary winding with one side of the line and between said first and second pairs of contacts and alternately connecting the contacts of each pair.
